UNITED STATES PATENT OFFICE

148,026

DESIGN FOR A RAILWAY CAR BODY

Basil E. Jones, Flossmoor, Ill., assignor to The
 Pullman Company, Chicago, Ill., a corporation
 of Illinois

Application February 18, 1946, Serial No. 126,642

Term of patent 14 years

(Cl. D66—1)

To all whom it may concern:

Be it known that I, Basil E. Jones, a citizen of the United States, residing at Flossmoor, in the county of Cook and State of Illinois, have invented a new, original, and ornamental Design for Railway Car Body, of which the following is a specification, reference being had to the accompanying drawings, forming part thereof.

In the drawings—

Fig. 1 is a general perspective view of a drawing room in the railway car body of my new design, and having certain portions broken away to afford a better illustration of the interior;

Fig. 2 is also a perspective view similar to Fig. 1, but showing the opposite side of the drawing room;

Fig. 3 is a horizontal mid-sectional view taken through the drawing room;

Fig. 4 is a vertical transverse sectional view showing one end of the room;

Fig. 5 is a vertical transverse sectional view showing the end of the room opposite that shown in Fig. 4;

Fig. 6 is a vertical longitudinal section taken through the room and showing the door side of the room;

Fig. 7 is a fragmentary transverse sectional view showing the toilet section;

Fig. 8 is also a vertical sectional fragmentary view showing the wash basin and mirror;

Fig. 9 is a vertical fragmentary longitudinal

section showing another view of the wash basin and the toilet; and

Fig. 10 is a general perspective view of a conventional railway car body of the type in which my new design is incorporated and having portions broken away to reveal the arrangement of the drawing room within the body and indicating the supporting trucks in dotted lines.

The characteristic features of the present design reside in the drawing room interior design shown in the drawings.

I claim:

The ornamental design for a railway car body, substantially as shown and described.

BASIL E. JONES.
